CANDELABRA

Xavier N. Benziger, New York, N. Y., assignor to Benziger Brothers, New York, N. Y., a firm composed of Xavier N. Benziger, Alfred F. Benziger, and Bernard A. Benziger

Application September 7, 1932. Serial No. 631,955

1 Claim. (Cl. 67—25)

This invention relates to candelabras particularly designed for use in places of worship.

In candelabras of this kind it is very desirable to be able to alter the design and general disposition of the arms supporting the candle holders to present different configurations for various purposes and to cause different ornamental effects to harmonize with surrounding furnishings. In candelabras, as heretofore in use, the arms extending sideways from the standard or center support were made adjustable to position them at different angles.

It is the particular purpose of the invention to provide the adjustable arms of candelabras with adjustable tips or ends by means of which a greater variety of designs can be obtained and the general adjustability of the candelabras be greatly enhanced to conform to surrounding conditions and different ideas of ornamentation.

Another object is to provide adjustable arms which are easy to operate and economical to manufacture. Further objects will become apparent in the following specification and the accompanying drawing, in which

Fig. 1 is an elevational view of a candelabra embodying the aforesaid adjustable arms and tips, in which are indicated in dotted lines various adjusted positions;

Fig. 2 is a fragmentary elevational view of one of the arms and its adjustable tip extended therefrom;

Fig. 3 is a part cross sectional view along the plane of line 3—3 in Fig. 2; and

Fig. 4 is a horizontal sectional view along the plane of line 4—4 in Fig. 2.

Like characters of reference denote similar parts throughout the several views and the following specification.

10 is a standard having a base 11. 12 is a slotted extension supporting preferably a candle holder 13. 14 and 15 are arms projecting sideways from extension 12 and consisting of, respectively, parallel disposed bars 14a and 14b, and 15a and 15b. The ends of these bars are slipped through the slot in extension 12 alongside of each other. A screw 16 acts as a joint fulcrum for upper bars 14a and 15a, and a thumb screw 17 as a joint fulcrum and adjusting screw for lower bars 14b and 15b.

18 are candle holders at the extremities of arms 14 and 15. Each of these holders 18 is provided with a downwardly extending shank 19, which is slotted at 20.

21 and 22 are adjustable tip members for, respectively, arms 14 and 15. Each of these tip members

consists of parallel disposed bars 21a, and 21b, and 22a and 22b. The ends of bars 15a and 15b are disposed within slot 20 of candle holder 18 at the extremity of arm 15 and alongside thereof the ends of bars 22a and 22b. A screw 23 acts as a fulcrum for upper bars 15a and 22a, and a thumb screw 24 serves as a fulcrum and adjusting screw for lower bars 15b and 22b. Similarly, bars 14a and 14b and bars 21a and 21b are disposed and fulcrumed within candle holder 18 at the end of arm 14 at the opposite side of the candelabra.

25 are candle holders having each a slotted shank 26, placed at convenient points in arms 14 and 15 and tip members 21 and 22. Each of these candle holders is provided with two fulcrum screws 27 for fastening them to the bars comprising the arms and tip members.

The operation and method of adjusting the candelabra is as follows:

The arms are formed of parallel disposed bars, so that the candle holders fastened thereto will always maintain their vertical position, as is well known in the art, this being based upon the principle of parallel motion of parallel bars. Arms 14 and 15 may be adjusted to any desired angle or position which can then be fixed by adjusting screw 17. The candle holders 25, being fastened to two parallel bars, as explained above, will remain in a vertical position; similarly candle holders 18.

Tip members 21 and 22 can be adjusted and fixed to any desired angle by tightening thumb screws 24.

It is quite apparent that, as is shown in dotted lines in Fig. 1, the arms 14 and 15 and tip members 21 and 22 can be given any desired position. This position can then be fixed by tightening thumb screws 17 and 24, providing a simple and easy operated means for producing a variety of designs of candelabras for different purposes.

It is obvious that a great many modifications may be made but still within the limits of the invention. So for instance, instead of the central standard, I may wish to employ a side bracket, or other form of support. Any number of candle holders may be placed onto the arms or the tip members.

It should therefore be understood that various other changes in the form, proportion and minor details of construction may be resorted to without departing from the principle or sacrificing any of the advantages of the invention as defined in the appended claim.

What I claim as new, is:

1. In a candelabra for the purpose specified, a support, arms projecting from the said support, adjustable tip members for the said arms, the arms and tip members consisting of pairs of parallel disposed bars, a candle holder having a slotted shank adapted to fit over adjacent pairs of bars of arms and tip members, a fulcrum pin through

the center of the shank serving as a fulcrum for one bar of each of the said adjacent pairs, and a regulating screw through the center of the shank serving as a fulcrum for the other bar of each of the said adjacent pairs, the said screw being adapted to hold the said adjacent pairs of bars in an adjusted position. 80
